SEWING MACHINE ATTACHMENT

Herbert H. Russell, New Haven, Conn., assignor to
 The Greist Manufacturing Company, New
 Haven, Conn., a corporation of Connecticut

Application December 26, 1942, Serial No. 470,147

20 Claims. (Cl. 112—135)

This invention relates to a sewing machine attachment, and more particularly to a sewing machine attachment designed to make a ruffle or gather in the material fed to the machine.

In devices of this character it has been desirable to provide for various adjustments, not only to make finer or coarser gathers or ruffles, but also to provide for the spacing apart of the ruffles, that is, to vary the number of sewing machine stitches between adjacent ruffles. In the past it has been more or less customary to provide a ruffler with such adjustments that it may be set to make a ruffle at every stroke of the needle bar, and at every sixth stroke of the needle bar, and at every twelfth stroke. Usually the attachments may also be adjusted so that plain sewing will be effected without any ruffles. It has been found that in many instances it would be desirable to provide for additional adjustments so that a range of work could be performed in addition to the one-stitch, six-stitch or twelve-stitch ruffles.

Also in the past the rufflers have in most cases been provided with ratchet wheels having deep and shallow teeth, these teeth controlling the engagement of an actuating pawl with a shoulder on the actuating lever of the ruffling blade. Such a construction required a different ratchet wheel or the equivalent thereof for each different setting of the attachment, so that if it were to have more than the three ruffling adjustments referred to above, namely, one-stitch, six-stitch and twelve-stitch, an excessive number of ratchet wheels would have to be employed.

One object of the present invention is to provide a sewing machine ruffler which may be attached to the ordinary household sewing machine, which has a wide range of adjustment.

A still further object of the invention is the provision of a sewing machine ruffler having a wide range of adjustments for various types of work, and so constructed that the adjustments may be performed quickly and easily even by an untrained operator.

A still further object of the invention is to provide a sewing machine ruffler of novel construction, and one which will have a wide variety of adjustments, which may be readily made while the attachment is in place upon the sewing machine, and which will not require removal and replacement of parts in the attachment.

A still further object of the invention is the provision of a sewing machine attachment which is capable of making one ruffle only in a large number of stitches, and is also capable of making a ruffle for each number of stitches which is an

even factor of this number. That is to say, if the greatest range of the device is a twelve-stitch ruffler, it can also be set to make a ruffle at every stitch, every second stitch, every third stitch, every fourth stitch, or every sixth stitch.

5 To these and other ends the invention consists in the novel features and combinations of parts to be hereinafter described and claimed.

In the accompanying drawing:

10 Fig. 1 is a side elevational view of a sewing machine attachment embodying my invention;

Fig. 2 is a side elevational view of the reverse side of the device;

Fig. 3 is a top plan view of the attachment;

15 Fig. 4 is a sectional view on line 4—4 of Fig. 1;

Fig. 5 is a sectional view on line 5—5 of Fig. 1;

Fig. 6 is a sectional view on line 6—6 of Fig. 1;

Fig. 7 is a sectional view on line 7—7 of Fig. 6; and

20 Fig. 8 is a side elevational view of the rotatable disk employed in the device.

To illustrate a preferred embodiment of my invention I have shown a ruffling attachment comprising a frame member 10 having an attaching member 11 for attachment to the presser bar of the sewing machine in the usual manner. Carried by this frame also is the usual separator blade 12, with which cooperates the movable ruffling blade 13.

30 The frame also is provided with an upstanding arm 14 mounting a pivot 15 upon which is rotatably mounted a disk member 16. Also pivoted at 15 is the operating lever 17 designed to be connected with the needle bar of the sewing machine in the usual manner, so that the member will be reciprocated or oscillated as the needle bar moves up and down. Upon the operating lever 17 is secured a resilient pawl member 18, the end of which is designed to engage in a row of openings 35 adjacent the periphery of the rotary disk 16 to actuate the latter in a step-by-step movement about its pivot. A stop pawl 19 is secured on the arm 14, and is designed to cooperate with the openings in the disk 16 to resist any tendency of the disk to move in a reverse direction. The pawl 19 may be secured in place by suitable means such as the rivet 21, and it will be seen that the stop pawl 19 is at the face of the disk 16 opposite that upon which the pawl 18 is located. It will also be understood that these pawls are resilient, so that their free ends may readily move out of the openings in the disk 16 and slide along the surface thereof upon relative movement of the disk and pawls in the proper direction.

Also pivoted on the pivot 15 is a lever 23 to the lower end of which at 24 is pivoted the carrier 25 of the ruffling blade 13. Formed integrally with the lever 23 is a plate 26 disposed flatwise against one side of the disk 16, and provided with a plurality of openings 27. Secured to the face of the plate 26 opposite the disk 16 is a plate 28 of open rectangular form, the upper and lower sides of which are provided with offset guide flanges 29 and 30, which, as shown more particularly in Figs. 4 and 5, are spaced from the plate 26 to provide a guideway in which is slidably mounted a block 31, so that this block may move lengthwise of the plate 26, or to the right and left, as shown in Fig. 4.

The block 31 carries a sleeve 32 within which is mounted a plunger 33 carrying upon its inner end a pin 34 designed to pass through one of the openings 27 of the plate 26. A spring 35 reacts between a shoulder 36 on the plunger 33 and a shoulder 37 on the sleeve 32 to normally urge the plunger toward the plate 26. A knob 38 is secured on the plunger 33 by which the plunger may conveniently be pulled outwardly against the tension of the spring 35 to move the pin 34 out of one of the openings 27 and adjust the block 31 along the plate 26 so as to position the pin in another of the openings 27. The knob may be conveniently secured in place by forming an annular recess 39 in the plunger 33, and placing in this recess a resilient split ring 40, so that the ring will be retained in the recess 39 and engage a portion of the knob to hold the latter in place.

The operating arm 17 is provided with a portion 42 extending beyond the pivot 15, and to this portion is pivoted a slotted cam 43 having cam faces 44 (Figs. 1 and 5) substantially intermediate its ends. The slot in the member 43 is adapted to embrace the sleeve 32 between the flanges 29 and 30 and the knob 38. It will be apparent from Fig. 1 that, upon each downward stroke of the needle bar, the cam member 43 will be raised and the cam portion 44 thereof will serve to move the knob 38 outwardly and move the plunger 33 away from the plate 26. Likewise, upon each upward stroke of the needle bar the cam member 43 will be moved downwardly, thus permitting the plunger 33 to be again pressed toward the plate 26 by the spring 35. It may here be stated that the lower portion 45 of the cam member 43, as shown in Fig. 5, is somewhat thicker than the upper portion 46, the two portions being joined by the inclined cam faces 44.

The actuating lever 23 of the ruffling blade is provided with an offset upwardly projecting arm 47 designed to be engaged by a screw 48 adjustably threaded in a sleeve 49 secured to the operating lever 17, so that upon the down stroke of the needle bar and actuating lever 17, the lower end of the screw 48 will contact the upper end of the arm 47 and return the ruffling blade 13 to its original position after an operating stroke thereof. It will be understood that the adjustment of the screw 48 in the sleeve 49 serves to adjust the stroke of the ruffling blade so as to make a wide or narrow gather or ruffle. That is to say, the length of the stroke which is given to the ruffling blade in a rearward direction by the screw 48 will determine the length of the forward stroke of the blade. It is desirable to provide some form of spring tension upon the screw 48 so that it will be held against play and against any tendency to turn. This is provided, as shown

in Figs. 6 and 7, by means of a resilient spring member 50 which embraces the screw 48 and the ends of which react against the edges of an opening 51 in the operating lever 17. As this member is held in place by the tendency of the free ends to expand against the edges of the opening 51, the tension is the same in both directions, so that an equal force is exerted upon the screw, regardless of the direction in which it may tend to turn. The member 50 may have threads formed therein to receive those of the screw 48.

In the form shown, a forward or operative stroke is imparted to the ruffling blade by connecting the latter to the disk 16, which, as has been described, is rotated in a step-by-step movement by the operating lever 17. It will be recalled that the ruffling blade is carried at the lower end of the pivoted actuating lever 23, and that this lever is formed integrally with the plate 26 which lies against the face of the rotatable disk 16, as shown in Fig. 4. The means which are provided to connect these parts consist of interengaging parts carried by the plate portion 26 of the actuating lever 23, and the disk 16, these interengaging elements being, in the form shown, the pin 34 and openings in the disk 16 with which the pin 34 engages. As shown in Fig. 8, the disk 16 is provided with a number of these openings of various sizes, so that they lie at different radial distances from the center of the disk, and are so arranged that, as the pin 34 may be set at various distances from the pivot 15 of the disk member 16, depending upon the opening 27 in which it is disposed, the pin may engage in a greater or lesser number of these openings during one turn of the disk 16, and thus vary the number of operative strokes given to the ruffling blade during one rotation of the disk.

Referring to Fig. 8, for example, it will be apparent that a large number of openings *a*, in this instance twelve, are arranged around the disk adjacent the periphery thereof. It is with these openings *a* that the pawls 18 and 19 engage, to effect step-by-step rotation of the disk, so that the latter is given a complete rotation every twelve strokes of the needle bar. If, for example, the pin 34 is placed in the opening 27 furthest to the right, as shown in Fig. 4, which will be the opening closest to the peripheral edge of the disk 16 or the opening designated by the numeral 1 in Fig. 8, the pin will lie against a solid part of the disk 16, and the plate 26 will never be connected with the disk. In this case, plain sewing will result, as no movement will be imparted to the ruffling blade. However, if the pin 34 is moved over into the next adjacent opening, or that designated by the numeral 2 in Fig. 8, the pin 34 will then engage in each of the openings *a* as they are brought opposite the pin, and when the disk is rotated the plate 26, lever 23 and ruffling blade 13 will be moved in an operative stroke. As the openings designated *a* are the same as those with which the pawl 18 engages, a ruffle or gather will be formed at each stroke of the needle bar, thus making the attachment a one-stitch ruffler.

If the pin 34 is moved over into the next adjacent opening 27, that marked with the numeral 3 on Fig. 8, it will be seen that the pin will no longer lie opposite the shorter openings *a*, but will lie opposite the inner ends of the longer openings designated *ab*. It will be seen that these openings alternate with the shorter openings *a* about the periphery, so that a ruffle will be formed every second stitch of the machine in-

stead of every stitch. In like manner the pin 34 may be moved into the next opening 27, in which position it will enter the openings designated c in Fig. 8, or, of course, in the opening abc at those radial positions where the opening c is in radial alignment with openings a and openings b. It will be seen that there are four of the openings c about the periphery of the disk 16, thus making the ruffler a three-stitch ruffler, so that it will make four ruffles every twelve strokes of the machine. Likewise, the pin 34 may be moved into the next adjacent opening 27 to be in position to enter the openings marked d (or abcd), of which three are located about the periphery of the disk. The next opening 27 of the plate 26 registers with the two openings e of the disk 16, and the innermost opening 27, that closest to the pivot 15, registers with the opening f, so that moving the pin 34 into these openings converts the attachment into a six- and twelve-stitch ruffler, respectively.

As shown in Figs. 1 and 2, as the operating lever 17 is moved up and down, the disk 16 will be rotated in a step-by-step movement, thus bringing the various openings in the disk 16 into registration with the corresponding openings 27. The disk will be moved upon the upstroke of the lever 17, and at the same time the cam plate 43 will be moved downwardly, so that when an opening a, b, c, d, e or f arrives opposite the pin 34, the cam surface 44 will have passed downwardly below the plunger 33, and will permit the pin to drop into this opening. Continued upward movement of the lever 17 will effect an operative stroke of the lever 23 and ruffling blade. As the operating lever starts downwardly, the disk 16 will be held against reverse movement by the stop pawl 19, and the cam plate 43 will be moved upwardly, thus withdrawing the pin 34 from the opening in the disk 16. At this time the lower end of the screw 48 will strike the upper end of the arm 47, moving the plate 26 upwardly or in a reverse direction with respect to the disk 16, thus moving the pin 34 out of registration with the opening in the disk 16 in which it was engaged, so that the pin lies opposite a solid part of the disk. Upon continued movements of the operating lever the pin will ride around upon a solid portion of the disk until an opening in the disk is again brought into registration with the pin, and a further ruffling operation is effected.

It will be apparent that for operation of the ruffling blade, the blade-actuating lever 23 is connected to the rotating disk 16, so that the latter positively moves the former by direct connection therewith. This connection, however, must be broken after an operative stroke in order that the ruffling blade may be returned to its original position during the downstroke of the lever 17, and the connection remains broken until time for a subsequent operation. Therefore, by means of the single rotative member 16, I am enabled to make a large number of adjustments intermediate the closest and most widely spaced ruffles, and these adjustments may be readily made by merely moving the slide 31 along the plate 26 so that the pin 34 rests in the proper one of the openings 27.

While I have shown and described a preferred embodiment of my invention, it will be understood that it is not to be limited to all of the details shown, but is capable of modification and variation within the spirit of the invention and within the scope of the claims.

What I claim is:

1. In an attachment for sewing machines, a frame, a ruffling blade carried thereby, a member rotatably mounted on the frame, means for rotating said member in a step-by-step movement from the needle bar of the machine, an actuating element for said blade, and interengaging means carried by said element and said rotatable member to cause said member to actuate the blade, said means comprising a part carried by said element and spring pressed into engagement with the means carried by said member.
2. A ruffler attachment for sewing machines, comprising a frame, a lever pivoted to the frame, a ruffling blade connected to the lever, a rotary member mounted on said frame to rotate about the pivot of said lever, means for rotating said member in a step-by-step movement from the needle bar of the machine, and a pin carried by said lever and engaging said member to effect actuation of the lever from said member.
3. A ruffler attachment for sewing machines, comprising a frame, a lever pivoted to the frame, a ruffling blade connected to the lever, a rotary member mounted on said frame to rotate about the pivot of said lever, means for rotating said member in a step-by-step movement from the needle bar of the machine, a pin carried by said lever and engaging said member to effect actuation of the lever from said member, and means for engaging said pin with said member at a plurality of points spaced circumferentially around the surface of the member.
4. A ruffler attachment for sewing machines, comprising a frame, a lever pivoted to the frame, a ruffling blade connected to the lever, a rotary member mounted on said frame, means for rotating said member in a step-by-step movement from the needle bar of the machine, a pin carried by said lever and engaging said member to effect actuation of the lever from said member, and means for engaging said pin with said member at a plurality of points spaced radially on said member.
5. A ruffler attachment for sewing machines, comprising a frame, a lever pivoted to the frame, a ruffling blade connected to the lever, a rotary member mounted on said frame, means for rotating said member in a step-by-step movement from the needle bar of the machine, a pin carried by said lever and engaging said member to effect actuation of the lever from said member, and means for engaging said pin with said member at a plurality of spaced points spaced circumferentially and radially on said member.
6. A ruffler attachment for sewing machines, comprising a frame, a lever pivoted to the frame, a ruffling blade connected to the lever, a rotary member mounted on said frame, means for rotating said member in a step-by-step movement from the needle bar of the machine, a pin carried by said lever and engaging said member to effect actuation of the lever from said member, and manual means for withdrawing said pin from said engagement.
7. A ruffler attachment for sewing machines, comprising a frame, a lever pivoted to the frame, a ruffling blade connected to the lever, a rotary member mounted on said frame, means for rotating said member in a step-by-step movement from the needle bar of the machine, a pin carried by said lever and engaging said member to effect actuation of the lever from said member,

and means operated by the needle bar for withdrawing said pin from said engagement to permit a return movement of the blade relatively to said member.

8. A ruffler attachment for sewing machines, comprising a frame, a lever pivoted to the frame, a ruffling blade connected to the lever, a rotary member mounted on said frame, means for rotating said member in a step-by-step movement from the needle bar of the machine, a pin carried by said lever and engaging said member to effect actuation of the lever from said member, means operated by the needle bar for withdrawing said pin from said engagement to permit a return movement of the blade relatively to said member, and means for effecting return movement of the blade.

9. A ruffler attachment for sewing machines, comprising a frame, a lever pivoted to the frame, a ruffling blade connected to the lever, a rotary member mounted on said frame, means for rotating said member in a step-by-step movement from the needle bar of the machine, a pin carried by said lever, said member having a plurality of series of openings therein, and said pin being adapted to be selectively engaged in the openings of a predetermined one of said series.

10. A ruffler attachment for sewing machines, comprising a frame, a lever pivoted to the frame, a ruffling blade connected to the lever, a rotary member mounted on said frame, means for rotating said member in a step-by-step movement from the needle bar of the machine, a pin carried by said lever, said member having a plurality of series of openings therein, and said pin being adapted to be selectively engaged in the openings of a predetermined one of said series, said openings being arranged in a plurality of series circumferentially of said member, and one series being spaced radially from another series.

11. A ruffler attachment for sewing machines, comprising a frame, a lever pivoted to the frame, a ruffling blade connected to the lever, a rotary member mounted on said frame, means for rotating said member in a step-by-step movement from the needle bar of the machine, a pin carried by said lever, said member having openings therein in which the pin is adapted to be engaged, said openings being arranged in a plurality of series circumferentially of said member, and one series being spaced radially from another series, and means for moving said pin radially of said member to engage the openings of any series thereof to vary the number of movements of the ruffling blade relatively to the strokes of the needle bar of the machine.

12. In an attachment for sewing machines, a frame, a ruffling blade carried thereby, a member rotatably mounted on the frame, means for rotating said member in a step-by-step movement from the needle bar of the machine, an actuating element for said blade, and interengaging means carried by said element and said rotatable member to cause said member to actuate the blade, and the means on said element being adjustable radially of said rotatable member to vary the number of movements of the ruffling blade relatively to the strokes of the needle bar of the sewing machine.

13. In an attachment for sewing machines, a frame, a ruffling blade carried thereby, a member rotatably mounted on the frame, means for rotating said member in a step-by-step movement from the needle bar of the machine, an actuating element for said blade, and interengag-

ing means carried by said element and said rotatable member to cause said member to actuate the blade, the means on said member being spaced radially thereof, and the means on said element being adjustable radially of said member to engage any of said means.

14. A ruffler attachment for sewing machines, comprising a frame, a lever pivoted to the frame, a ruffling blade connected to the lever, a rotary member mounted on said frame, means for rotating said member in a step-by-step movement from the needle bar of the machine, a pin carried by said lever and engaging said member to effect actuation of the lever from said member, said pin being movable with respect to said lever, a knob on said pin by which the latter may be manually moved, an annular recess in the pin, and a split ring seated in said recess and engaging the knob to secure the latter to the pin.

15. In an attachment for sewing machines, a frame, a ruffling blade carried thereby, a member rotatably mounted on the frame, means for rotating said member in a step-by-step movement from the needle bar of the machine, an actuating element for said blade, and interengaging means carried by said element and said rotatable member to cause said member to actuate the blade, the means on said member being spaced radially and circumferentially thereof, and the means on said element being movably mounted thereon for adjustment in a direction radially of said element to engage any of said means.

16. In an attachment for sewing machines, a frame, a ruffling blade carried thereby, a member rotatably mounted on the frame, means for rotating said member in a step-by-step movement from the needle bar of the machine, an element connected to said blade to actuate the latter, and said member and element having interengaging means thereon to actuate said element by the rotation of said member, and the means on said member being spaced radially and circumferentially thereof to vary the number of strokes of the blade during a complete revolution of said member.

17. In an attachment for sewing machines, a frame, a ruffling blade carried thereby, a member rotatably mounted on the frame, means for rotating said member in a step-by-step movement from the needle bar of the machine, an element connected to said blade to actuate the latter, and said member and element having interengaging means thereon to actuate said element by the rotation of said member, and the means on said element being movable with respect to said member in a direction parallel to the axis of the latter to be withdrawn from engagement therewith.

18. In an attachment for sewing machines, a frame, a ruffling blade carried thereby, a member rotatably mounted on the frame, means for rotating said member in a step-by-step movement from the needle bar of the machine, means for connecting said blade to said member for actuation thereby, said means comprising a plurality of series of openings in said member and an element connected to the blade and carrying a part adapted to be selectively received in the openings of a predetermined one of said series, said part being movable toward and away from said member in a direction parallel to the axis of the latter.

19. In an attachment for sewing machines, a frame, a ruffling blade carried thereby, a member rotatably mounted on the frame, means for rotating said member in a step-by-step movement

from the needle bar of the machine, means for connecting said blade to said member for actuation thereby, said means comprising a plurality of series of openings in said member and an element connected to the blade and carrying a part adapted to be selectively received in the openings of a predetermined one of said series, said part being movable toward and away from said member in a direction parallel to the axis of the latter, and means for withdrawing said part to permit said rotatable member to advance without moving the blade.

20. In an attachment for sewing machines, a frame, a ruffling blade carried thereby, a member rotatably mounted on the frame, means for ro- 15

tating said member in a step-by-step movement on the upstroke of the needle bar of the machine, means for connecting said blade to said member for actuation thereby, said means comprising a plurality of series of openings in said member and an element connected to the blade and carrying a part adapted to be selectively received in the openings of a predetermined one of said series, said part being movable toward and away from said member in a direction parallel to the axis of the latter, and means for withdrawing said part on the downstroke of the needle bar to permit a return movement of the blade when said rotatable member is idle.

HERBERT H. RUSSELL.
